UNITED STATES PATENT OFFICE.

EDWARD W. MOON, OF YOUNGSTOWN, NEW YORK, ASSIGNOR, BY DIRECT AND MESNE ASSIGNMENTS, OF TWENTY PER CENT TO CHARLES RAY KASKELL AND TWENTY PER CENT TO LE GRAND F. KIRK, BOTH OF YOUNGSTOWN, NEW YORK.

ELECTRICAL CUT-OUT.

Application filed April 16, 1926. Serial No. 102,484.

The invention has relation to fuse sockets, having for an object to provide an improved fuse socket wherein a coin or other round disk is not admissible for the purpose of 5 taking the place of a fuse plug in making the electrical connection.

The invention consists in the novel construction and combinations of parts, as set forth in the appended claims.

10 In the accompanying drawings illustrating the invention, Figure 1 is a central longitudinal section of the invention; Figure 2 is a similar view of the ordinary fuse socket with the plug removed and a coin 15 inserted in place thereof, and Figure 3 is a plan view of a double socket constructed in accord with the invention and having the fuse plugs removed.

In these drawings the numeral 1 designates the porcelain fuse block having the 20 socket 2, and provided at the inner end of said socket with a contracted recess 3' wherein is located an insulation washer or lining 3 also recessed or of cupped form neatly fitting 25 said block recess and provided with an outer flange at right angles thereto. Located in the bottom of said recess of and upon said insulation lining is an electrical contact or copper terminal 4 with which the fuse plug 30 is adapted at its inner end to contact, the depth and diameter of the recess of said washer being such that in case a coin or washer or other round disk is inserted within the socket to take the place of a fuse plug 35 which has blown (see Figure 2 of the drawing) the arcuate portion of said coin admissible within said recess will be upheld by the marginal portion of the recess of the insulation washer out of contact with said 40 terminal.

It is a common practice to insert coins or washers to take the place of the fuse plugs the fuses of which have blown, as shown in Figure 2 of the drawings, and in the event 45 of a short circuit or other defective wiring, in which case it is necessary for the fuse to blow and prevent further damage, the coin would not function as a fuse, and damage such as fires, etc., would result as a 50 consequence.

The porcelain body of the fuse plug in order to cooperate with the fuse socket stated, is provided with a contracted inner extension or pin 5, adapted to enter the recess of the insulation washer freely and 55 without contacting with the side walls thereof, said pin being of a diameter considerably less than the diameter of said socket and having a contact device or copper terminal 6 at its inner end for making the electrical 60 connection with the terminal 4, said fuse plug being otherwise constructed as usual and having the external thread 7 of rolled sheet brass, adapted to engage the internal 65 thread 8 of the fuse socket, also of rolled sheet brass. The copper terminal 6 of the fuse plug will be held thereby in contact with the copper terminal 4 of the socket.

I claim:

1. A fuse block having a socket provided 70 with a contracted recess in the inner end wall thereof and a cupped insulation lining neatly fitting the recess of said block and having an outer flange at right angles thereto, and an electrical terminal located upon said insulation lining at the inner end of said recess, the depth and diameter of the recess of said insulation lining being sufficient to uphold the arcuate portion of a disk admissible within said recess out of contact 75 with said electrical terminal.

2. The combination with a base of dielectric material, of a fuse plug socket having an end wall provided with a central opening therethrough, an insulating washer overlying said end wall of said socket and having a central cup shaped portion registering with said central opening, a contact member within said cup shaped portion, securing said insulating washer and thereby 80 securing said socket to said base, said contact member having no portion thereof extending beyond said cup shaped portion, and a fuse plug having a projecting contact 85 adapted to engage said socket contact entirely within said cup shaped portion.

In testimony whereof I affix my signature.

E. W. MOON.
